Primary Examiner—Paula A. Mortimer(74) *Attorney, Agent, or Firm*—Dorsey & Whitney LLP(57) **CLAIM**

Th ornamental design for the flexible pouch, as shown and described.

DESCRIPTION

FIG. 1 is a perspective view of the front of one embodiment of the edging of the present invention;

FIG. 2 is plan view of the top of the embodiment of the invention depicted in FIG. 1;

FIG. 3 is an elevational view of the front of the embodiment of the embodiment of the invention depicted in FIG. 1;

FIG. 4 is an elevational view of the right of the embodiment of the invention depicted in FIG. 1;

FIG. 5 is an elevational view of the left of the embodiment of the invention depicted in FIG. 1;

FIG. 6 is an elevational view of the front of the embodiment of the invention depicted in FIG. 1; and,

FIG. 7 is an elevational view of the rear of the embodiment of the invention depicted in FIG. 1.

The structure shown in broken lines in the Figures is not part of the design sought to be patented, but instead shows the environment of the claimed design.
